UNITED STATES PATENT OFFICE.

HARVEY O. SHERRICK, OF ELIDA, OHIO.

HEN'S NEST.

1,172,638.

Specification of Letters Patent. Patented Feb. 22, 1916.

Application filed October 20, 1915. Serial No. 56,892.

To all whom it may concern:

Be it known that I, HARVEY O. SHERRICK, a citizen of the United States, residing at Elida, in the county of Allen, State of Ohio, have invented a new and useful Hen's Nest; and I do hereby declare the following to be a full, clear, and exact description of the invention, such as will enable others skilled in the art to which it appertains to make and use the same.

This invention relates to an improved hen's nest and more especially to that class having for its object the provision of means for retaining or trapping the hen in the nest, particularly when sitting, in order to avoid being annoyed by the other hens.

Another object of the invention is the provision of a nest of this character, in which simple, efficient and practical features of construction are involved.

One of the features of the invention is the provision of a suitable housing, which may be constructed of any suitable material, preferably galvanized tin and the like, and provided with a hinged closure, designed to be swung upwardly when opening the same, and adapted for use in conjunction with improved means for propping the closure in an open position, said propping means being of such improved construction, and pivotally arranged in the housing, as to be tripped by the hen as the hen enters the housing, thereby throwing the laterally extending arms of the propping means from the path of angular members or lugs upon the inner face of the closure, thereby permitting the closure to gravitate upon its hinged connection to a closed position, in order to trap the hen in the housing.

In practical fields the details of construction may necessitate alterations, falling within the scope of what is claimed.

The invention comprises further features and combination of parts, as hereinafter set forth, shown in the drawings and claimed.

In the drawings; Figure 1 is a view in front elevation of the housing in which the nest is built, showing the closure in an open position. Fig. 2 is a sectional view on line 2-2 of Fig. 1, illustrating the closure propped open. Fig. 3 is a vertical sectional view showing the closure in its closed position. Fig. 4 is an enlarged detail perspective view of the pivoted propping means.

Referring more especially to the drawings, 1 designates a suitable housing, which

may be any suitable shape or configuration, and in which a nest for a hen may be built. The front wall of the housing is provided with an opening 2, and hinged at 3 adjacent the upper edge of the opening is a closure 4. Secured upon the inner face of the closure are two angle members 5, which are adjacent the hinge connection of the closure. A rod 6 extends transversely of the housing in its upper portion, and somewhat close to where the closure is hinged. The opposite ends of the rod 6 are secured in the opposite sides of the housing, as shown at 7, to prevent rotating of the rod 70 and endwise movement thereof. Pivoted upon the rod 6 as shown at 8 is a tripping member 9. This tripping member consists of a single length of wire, bent upon itself in two places as shown at 10, to form downwardly extending loop arms 11. The sides 12 of the loop arms at their upper parts are coiled about the rod 6 as shown at 8 to afford the pivotal connections. The sides 13 of said looped arms extend upwardly 80 and merge into the transverse part 14, which extends beyond the rod 6, so that the arms 13 may engage the rear part of the rod 6 to assist in holding the tripping member 9 in the positions to which it may be moved. 85 The sides 12 beyond the coils 8 are formed in laterally extending arms 15, which are positioned at right angles to the arms 11, and which arms 15 are designed to engage the lateral parts or lugs 16 of the angle 90 members or plates 5, so as to hold the closure propped open, as illustrated in Fig. 2. The back of the housing is provided with guides 18 to receive a sliding closure 19. The top of the housing is provided with an 95 opening 20 to permit ventilation.

In use the closure 4 is raised as shown in Figs. 1 and 2, and the tripping member 9 is set as disclosed in Figs. 2 and 4, so that the arms 11 extend downwardly, while the arms 15 extend laterally in order to engage the lugs or parts 16 of the angle members or plates 5, thereby supporting the closure 4, as seen in Figs. 1 and 2. A hen's nest (not shown) may be built in the housing, 105 and when the hen enters the housing, its body contacts with the arms 11 and moves the arms in the direction of the arrow *a*, thereby withdrawing the arms 15 from the path of the parts or lugs 16 of the angle 110 members or plates 5, in which case the closure 4 will fall to a closed position, as seen

in Fig. 3, and owing to the front wall of the housing being inclined, the closure 4 will remain closed tightly, and owing to the weight of the closure, the hen is prevented 5 from lifting and forcing the closure open with its body, thereby in this manner preventing the escape of the hen.

From the foregoing it is to be observed that the hen is easily retained in the housing and on its nest, particularly when sitting, thereby avoiding being annoyed by the other hen. However, when it is desired to release the hen the slide closure 19 may be removed, thereby permitting the hen to pass 15 out at the rear of the nest.

The parts 13 and the part 14 coöperate with the side of the rod 6 opposite the rear of the housing, so as to offer frictional resistance, to hold the tripping member in 20 the position set, until tripped by the hen entering the entrance opening.

The invention having been set forth, what is claimed as new and useful is:

Copies of this patent may be obtained for five cents each, by addressing the "Commissioner of Patents, Washington, D. C."

An improved nest comprising a housing having its front wall provided with a hinged closure having upon its inner face a pair of angular members, a rod arranged transversely of the housing near its upper portion adjacent the hinged connection of the closure, a tripping member constructed from a single length of spring wire pivoted upon said rod and having lateral arms adapted to engage the angle members of the closure to prop the closure open; said tripping member having downwardly depending arms in the path of the hen as it enters the housing, said downwardly depending arms having spring means extending upwardly to engage said transverse rod.

In testimony whereof I have signed my name to this specification in the presence of two subscribing witnesses.

HARVEY O. SHERRICK.
